UNITED STATES PATENT OFFICE.

HENRY H. WAIT, OF CHICAGO, ILLINOIS.

STEAM-EQUALIZER.

9,38,356.

Specification of Letters Patent. Patented Oct. 26, 1909.

Application filed September 30, 1908. Serial No. 455,564.

To all whom it may concern:

Be it known that I, HENRY H. WAIT, a citizen of the United States, residing at Chicago, in the county of Cook and State of Illinois, have invented a certain new and useful Improvement in Steam-Equalizers, of which the following is a full, clear, concise, and exact description.

This invention relates to apparatus adapted to receive exhaust steam from engines, absorb the heat from such steam and equalize the pressure so as to give off a continuous supply of steam at an approximately constant pressure, suitable for use in low-pressure turbines. My object is to provide an improved apparatus of this type which will be simple and effective and will present the minimum resistance to the steam received from the engine so as to avoid back-pressure.

Steam regenerators have heretofore been constructed in which the exhaust steam is blown through small openings in a submerged pipe, into a body of water, the water being violently agitated thereby and acting to absorb the heat of the exhaust steam, whereby upon the lowering of pressure by the withdrawal of steam for use in the turbine, the heated water will give off such steam as required; the exhaust from the engine being received at sufficiently frequent intervals to supply the heat required. There is in the use of this type of regenerator a certain back-pressure exerted upon the primary engine which supplies the exhaust steam, because the main openings letting the steam into the water are generally about two feet below the surface of the water. This makes a very considerable static head for the steam to overcome; and as the steam is delivered in sudden puffs the resistance offered by the inertia of the water which must be displaced gives rise to a still greater back-pressure.

In accordance with my invention the steam is not blown into the water or other heat-retaining fluid below the surface thereof, but a substantially free and unimpeded, restricted current of steam is directed into entraining contact with the fluid, and this contact causes a circulation of the fluid such that the portions receiving the steam impact will flow toward the cooler portions of the fluid body and preferably into repeated contact with the steam current, the fluid finally returning to the place of im-

pact. The steam is preferably directed into repeated contact with the surface of the fluid by means of a helical steam chamber through which the steam flows in such a manner that at each convolution it passes across the fluid surface, and finally returns through a central pipe, around the outside of which said helical chamber is formed. A similar helical chamber is preferably provided for the water or other fluid, so that such fluid set in motion by the impact of the steam follows a helical path, at each convolution of which it is exposed to the steam. The heated fluid is thus caused to mingle thoroughly with the portions which are cooler, so that fresh surfaces are continually being exposed, and the heat thus efficiently absorbed.

I will explain my invention in detail and describe further features thereof by reference to the particular embodiment shown in the accompanying drawing, which is illustrative of the principles involved.

Figure 1 is a sectional elevation of my improved steam regenerator; Fig. 2 is a sectional plan view thereof; and Fig. 3 is a cross-section on line 3—3 of Fig. 1.

The same reference characters indicate the same parts wherever shown.

In the form of equalizer shown, the container 4 is a horizontal hollow cylinder having pipes 5 and 6 extending longitudinally therethrough, and plates 7, 7, forming a double helix throughout the container, said plates extending from the outer surfaces of said pipes to the inner walls of the container. The container will be filled with water up to approximately the level indicated, which will not ordinarily rise above the under surface of the upper pipe 5. The surface of the water forms one wall of a helical steam chamber formed by the plates 7, 7, about the upper pipe 5, said helical chamber thus forming constricted passages constituting, in effect, nozzles for directing a substantially free and unimpeded current of steam into entraining contact with the surface of the water. At one end, said steam chamber is in communication with a source of exhaust steam 8, and at the other end it communicates with an inlet 9 leading into the interior of the pipe 5. At the opposite end of said pipe 5 there is an outlet 9^a from which the steam is withdrawn to be utilized in a low-pressure turbine or otherwise. As shown, the outlet pipe 9^a leads into a trap

14 adapted to receive and collect any entrained water, and a pipe leads from said trap to the turbine or other device which is to utilize the steam. Baffle plates 16, 16, are preferably provided within the pipe 5 to reduce the speed of the steam current and assist in equalizing the pressure thereof. The plates 7 also form a helical chamber for the fluid surrounding the lower pipe 6. Said pipe 6 has an inlet opening 11 at one end thereof, and an outlet opening 12 at the other end, said openings being in communication with the helical water chamber, so that the water after flowing through the helical convolutions in one direction will be returned through the pipe in the opposite direction.

Suitable means will be provided for preventing the fluid in the container from rising above a given level. As shown, an overflow pipe 13 leads from the water chamber to the chamber 14 of the trap, which is provided with a float-valve 15 adapted to open when the water rises above a predetermined point. The regenerated steam is conducted from the chamber 14 through the outlet pipe 10.

The equalizer may also be provided with an automatic escape-valve for steam, adapted to open if the steam pressure should for any reason rise above a predetermined value.

I preferably provide deflecting plates within the container, to assist in directing the steam and water currents. The plates 17, 17, assist in directing the surface water downward so that it may pass under the pipe 6 and rise again in the next compartment or convolution of its helical passage. The steam-deflecting plates 18 are preferably sheets of metal fastened at one edge to the side of the upper or steam pipe 5, and conforming in shape to the pitch of the convolutions of the helical steam chamber. The free edges of said plates are adjustably supported so that the lower surfaces thereof may be brought nearer to or farther from the surface of the water in the corresponding compartment, whereby the impact of the steam upon the water, and the amount of surface water to be displaced in each compartment may be regulated.

A coil spring at the inner end of the plate 18 may be employed in order to maintain the outer or free end of said plate in close engagement with steam-pipe 5.

The operation of the apparatus is as follows: Exhaust steam admitted from the pipe 8 is carried downward around the side of the pipe 5, in the first compartment, and is blown through the narrow horizontal space between the surface of the plate 18 and the surface of the water. After passing through this opening the steam current is conducted in a spiral path around the pipe 5 into the next compartment, where it again

blows through the opening next to the surface of the water, and so continues in its travel through the helical chamber, being repeatedly directed into impact with the water in the successive compartments, until, 70 in the last compartment, it passes through opening 9 into the interior of the pipe 5. Its passage through said pipe is retarded by the baffle plates 16. The entraining contact of the steam current against the surface of the 75 water in each compartment draws the water laterally across the container so that it tends to circulate around the lower pipe 6. Such circulation is assisted by the directing plates 17, and the water with which the steam contacts in each compartment is carried down around the pipe and on into the next compartment, and so continues its passage through the helical chamber, being brought into repeated contact with the steam current 80 and finally returning to the starting point through the pipe 6. The heat of the steam is thus effectively communicated to the water by a series of contacts which throw the water into a violent churning motion, 85 the heated portions being made to pass downwardly into the colder portions of the body fluid, which is thus caused to absorb the heat. The violent surging of the steam received is retarded and the pressure thereof 90 equalized, so that the delivery from the pipe 9 will be approximately constant in pressure.

It will be observed that the passage of steam longitudinally through the vessel by way of the helical steam chamber is in a 100 direction opposite to the longitudinal flow of water through its helical chamber. One object of this arrangement is to make the head produced by the friction of the steam on the water partially compensate for the 105 difference in head caused by the drop in pressure of the steam as it passes through the successive compartments. If the arrangement were such that the water and steam traveled longitudinally in the same 110 direction, instead of in opposite directions, there would be a tendency for the water to pile up still higher in the successive compartments. With the arrangement as shown, the flow of water in its helical chamber is 115 toward the left hand end of the container, while the helical flow of the steam is toward the right hand end; so that the tendency of the water to pile up at the left hand end of the container is opposed by the effect of the 120 slightly higher steam pressure in the first steam compartments.

I claim:

1. In a steam equalizer, the combination with a vessel adapted to contain heat-retaining fluid, of means for directing a constricted current of steam through said vessel and into entraining contact with the free surface of such fluid, the vessel being arranged to cause the fluid current set up by the friction 125 130

of the steam upon the surface of such fluid to circulate so as to come into repeated contact with the steam current.

2. In a steam equalizer, the combination 5 with a container for fluid, of a steam chamber above the fluid level, and a guide plate close to the fluid surface adapted to cause a constricted passage of steam under said plate into frictional contact with the fluid 10 surface.

3. In a steam equalizer, containing a body 15 of heat-retaining fluid, the combination with means for directing a constricted current of steam into frictional contact with the free surface of such fluid, of directing means for said fluid adapted to cause the portions receiving the steam impact to flow toward the cooler portions of the body and thence to return to the place of impact.

20 4. In a steam equalizer, the combination with a horizontally disposed container for heat-retaining fluid, a constricted passageway for steam extending above the body of fluid in said container and providing means 25 for directing a current of steam transversely in contact with the surface of such fluid.

5. In a steam equalizer, the combination 30 with a container for fluid, of means adapted to direct a restricted current of steam into repeated entraining impact with a free surface of the fluid in such container, and directing plates adapted to cause a circulation 35 of the heated fluid through the cooler portions of the body and past the places of steam-impact in series.

6. A steam equalizer having a helical water chamber, and a helical steam chamber parallel therewith, said chambers being constructed to bring the steam into impact with 40 the surface of the water at each convolution; said helical chambers being so constructed and having inlet and outlet openings so located as to produce a longitudinal flow of the water in the opposite direction 45 from the longitudinal flow of the steam.

7. In a steam equalizer, the combination 50 with a container for heat-retaining fluid, of a pipe extending longitudinally of said container above the body of fluid therein, and guide plates between the outer surface of 55 said pipe and the inner wall of the container, forming a helical chamber around said pipe, said chamber being in communication with a source of exhaust steam at one end and being in communication with the interior of said pipe at the other end, said pipe having an outlet for steam at the opposite end from that at which it receives steam from said helical chamber.

60 8. In a steam equalizer, the combination with a container for heat-retaining fluid, of a pipe extending longitudinally of said container above the body of fluid therein, guide plates between the outer surface of said pipe 65 and the inner wall of the container, forming

a helical chamber around said pipe, said chamber being in communication with a source of exhaust steam at one end and being in communication with the interior of said pipe at the other end, said pipe having an outlet for steam at the opposite end from that at which it receives steam from said helical chamber, and baffle plates in said pipe between the inlet and outlet openings thereof.

75 9. In a steam equalizer, the combination with a container for heat-retaining fluid, of a pair of pipes extending longitudinally in the interior of said container, one of said pipes being below the level of the fluid in 80 said container, and the other pipe being above such level; guide plates forming a double helix around said pipes, the lower pipe having a water-inlet opening at one end and a water-outlet opening at the other 85 end, whereby the water is caused to flow through the interior of said lower pipe from end to end and a helical path around the outside thereof; the upper pipe having a steam inlet opening at one end and a steam 90 outlet opening at the other end, a helical steam chamber being formed around said upper pipe, said steam chamber being in communication with a source of steam at the 95 opposite end from the opening into said upper pipe.

10. In a steam equalizer, the combination with a horizontally disposed container divided into a series of transverse compartments for steam and water, of means for 100 directing the steam and water currents across each compartment in the same direction and through the series of compartments in opposite directions.

11. In a steam equalizer, the combination 105 with a container adapted to be partially filled with fluid, of plates dividing said container into a series of compartments, said compartments being in communication above the fluid level and having means for directing a flow of steam laterally through constricted passages across the surface of fluid in each compartment and through said compartments in series.

12. In a steam equalizer, the combination 115 with a container for fluid, of a pipe above the level of fluid in said container, means for directing a current of steam around the exterior of said pipe next to the fluid surface, a sheet metal deflecting plate secured 120 at its upper edge to the side of said plate, and extending around the under surface of said pipe, the free edge of said plate being adjustably supported, whereby the area of the steam passage bounded by the fluid surface may be regulated.

13. In a steam equalizer the combination 125 with a container for heat-retaining fluid, of a pipe extending longitudinally of said container above the body of fluid therein, and a 130

helical steam chamber extending around said pipe, said chamber being in connection with a source of exhaust steam at one end, and being in connection with the interior of said pipe at the other end, said pipe having an outlet for steam at the opposite end from that at which it receives steam from said helical chamber.

14. In a steam equalizer, the combination with a vessel containing a body of water as a heat-absorbing and heat-disengaging medium, a nozzle for causing a free and unimpeded jet of steam to forcibly impinge on portions of said water and thereby to propel such portions in the direction of impact of said jet of steam.

15. In a steam equalizer, the combination with a vessel containing a body of water as a heat-absorbing and heat-disengaging medium, of means for causing a free and unimpeded jet of steam to forcibly impinge on portions of said water and thereby to propel such portions in the direction of impact of said jet of steam and means for conducting water from the colder portions of said body of water to the point of impact of said jet of steam.

16. In a steam equalizer, the combination with a vessel containing a body of water which acts as a heat-absorbing and heat-disengaging medium, a nozzle for causing a jet of steam to forcibly impinge on the surface of said body of water at one or more points thereof and thereby to propel portions of said water from the points of impact of said steam.

17. In a steam equalizer, the combination with a vessel containing a body of water which acts as a heat-absorbing and heat-disengaging medium, a nozzle for directing a free jet of steam at a high velocity into frictional impact with portions of said body of water and thereby to heat such portions of the water and to carry the heated portions in the direction of impact of said jet of steam, and means for replacing the portions thus carried away by water from the colder portions of said body of water.

18. In a steam equalizer, the combination with a vessel containing a body of water, said vessel being provided with guiding means for guiding the circulation of the water therein, a nozzle for directing a jet of steam into impact with said body of water in a direction to cause the flow of water in the path provided by said guiding means.

19. In a steam equalizer, the combination with a vessel containing a body of water, a nozzle for directing a jet of steam into impact with said body of water, and guiding means for successively conducting away the portions of water receiving the impact of the steam and for leading the colder portions of the body of water to the place of impact.

In witness whereof, I, hereunto subscribe my name this 18th day of September A. D., 1908.

HENRY H. WAIT.
